UNITED STATES PATENT OFFICE

SJUNE SVENSSON, OF KROKOM, SWEDEN

METHOD OF CHARGING CELLULOSE BOILERS AND THE LIKE AND DEVICE ADAPTED THEREFOR

Application filed June 6, 1928, Serial No. 283,411, and in Sweden February 11, 1928.

This invention relates to a method and devices for charging cellulose boilers and the like by using steam for the packing of the wood chips in the boiler as for instance is shown in the American Patent No. 1,593,147.

According to the present invention two adjustable jets of steam are caused to coact in such a way that they together assume the shape of a conical mantel surface, which is enlarged downwards, and that the top angle of said mantel surface is enlarged according as the boiler is filled with wood chips in order to obtain the most favourable distribution of the wood chips during the entire charging of the boiler. Suitably a tube shaped jet of steam, which is directed downwards is caused to assume the shape of a conical mantel surface thereby, that another tube shaped jet of steam which has a smaller outer diameter is directed upwards in opposite direction to the other. If the pressure of the upward jet of steam is increased the top angle of the conical mantel surface is increased and vice versa. A jet of steam in the form of a disc or a conical mantel surface, which is enlarged downwards is actuated by a downwards directed, tube shaped jet of steam in such a way, that the former jet of steam, at the beginning of the charging of the boiler with wood chips, forms the mantle surface of an elongated cone, the top angle of which is increased, according as the wood chips are charged into the boiler, by diminishing the pressure of the downwards directed jet of steam.

In the accompanying drawings are shown schematically two embodiments for performing the method.

Figs. 1 and 3 show the first embodiment, Fig. 1 is a vertical section through the lower part of the device, and Fig. 3 a cross section along the line 2—2 in Fig. 1.

The device consists of an outer, wider pipe *a* and a narrower pipe *b* inserted in the former. The free end of the pipe *b* projects beyond the mouth of the pipe *a*, and the lower part of the pipe *b* is held centred, suitably by means of radial supports *c*. The pipe *b*, in the lower part outside the mouth of the wider pipe, is provided with side openings *d*, and

its mouth is closed by a cap *e*, which leaves a ring shaped space with less diameter than that of the wider pipe in communication with the inside of the pipe *b* by the openings *d*. Both pipes are connected to a steam piping. Steam is supplied adjustably to both pipes and flows out partly through the space between the outer and the inner pipe, partly through the ring shaped space between the pipe *b* and the cap *e*. Both jets of steam meet each other, and by suitably regulating the steam a more or less conical downwards enlarged mantle surface of steam can be obtained, which steam distributes the falling wood chips.

Figs. 2, 4 show the other embodiment. Fig. 2 is a vertical section through the lower part of the device, and Fig. 4 a cross section along the line 4—4 in Fig. 2.

As in the former case the device consists of an outer wider pipe *a* and an inner narrower pipe *b*, to which steam can adjustably be supplied. The free end of the pipe *b* projects beyond the mouth of the pipe *a*, and the lower part of the pipe *b* is held centred, suitably by means of radial supports *c*. The pipe *b*, in its lower part, is provided with openings *d*, which lead to a ring shaped slot *f* arranged between an adjustable, suitably conical nut *g* and a cap *h* closing the end of the pipe. The nut may be omitted, in which case a greater number of openings is arranged in the pipe *b*, suitably in two or three rows fixed above each other.

The pipes *a* and *b* may each be provided with valves (not shown), or they may have a common adjusting member, arranged to be actuated manually or automatically by an electrically actuated or spring actuated device, which is arranged on the charging device, or by another power source from which the driving power is transmitted by means of a belt or the like, whereby the setting of the adjusting member is made in timed relation to the filling of the boiler.

Having now described my invention, what I claim as new and desire to secure by Letters Patent is:

1. A device for filling boilers for cellulose and the like by using steam for the packing

of the wood chips in the boiler, said device comprising two concentric pipes spaced from each other and providing between them an annular steam-supply opening, said pipes being adapted to be arranged centrally in the neck of the boiler, the free end of the inner smaller pipe projecting beyond the end of the outer larger pipe, the projecting end of the inner pipe being provided with 10 side openings, and means associated with said pipe for closing the end thereof and providing a ring-shaped radially-extending steam delivery space which communicates with the inner tube through said side opening, where- 15 by the steam issuing simultaneously from both pipes forms a conical sheet by which the wood chips are packed into the boiler.

2. A device for filling boilers for cellulose and the like by using steam for the packing 20 of the wood chips in the boiler, said device comprising two concentrically - arranged pipes adapted to be placed centrally in the neck of the boiler, radial supports separating said pipes, the space between them con- 25 stituting an annular space for the delivery of steam, the inner pipe projecting beyond the outer pipe and provided with side open- 30 ings, a cap closing the end of the inner pipe, and means associated with said cap for pro- 35 viding a ring-like opening communicating with the side openings of the inner pipe and through which steam is delivered from the inner pipe in an outwardly-diverging circular jet which intersects the radial jet of steam delivered from the annular space between 35 the pipes thereby forming a conical sheet.

3. The method of filling boilers for cellulose and the like by using steam for the pack- 40 ing of the wood chips in the boiler, which consists in delivering the steam into the neck of the boiler in two outwardly-diverging non-parallel annular jets which intersect each other, and thereby form a cone-shaped sheet which engages the chips and packs them into 45 the boiler and regulating the relative pressure of the steam forming each annular jet thereby varying the shape of the conical sheet.

In witness whereof, I have hereunto signed
50 my name.

SJUNE SVENSSON.
